UNITED STATES PATENT OFFICE.

FREDERICK SELBY, OF CHESTER, PENNSYLVANIA, ASSIGNOR TO JAMES C. FENDER, OF SAME PLACE.

DESIGN FOR A FILLING-BLOCK FOR FIREPROOF FLOORS.

SPECIFICATION forming part of Design No. 30,570, dated April 18, 1899.

Application filed March 22, 1899. Serial No. 710,108. Term of patent 14 years.

To all whom it may concern:

Be it known that I, FREDERICK SELBY, a citizen of the United States, and a resident of Chester, Pennsylvania, have invented and produced a new and original Design for a Filling-Block for Fireproof Floors, of which the following is a specification.

My design for a filling-block for fireproof floors is fully shown in the accompanying drawings, in which—

Figure 1 is an elevation of the filling-block. Fig. 2 is a cross-section on the line $x-x$, Fig. 1. Fig. 3 is a cross-section on the line $y-y$, Fig. 1; and Fig. 4 is a perspective view of the filling-block.

The essential feature of the design is a filling-block for the purpose specified approximately I-shaped in cross-section, comprising a central web, top and base flanges connected by the same, overhanging projections at the ends of the block, a series of vertical and inclined ribs connecting the top and base flanges, and side projecting portions on said ribs and top and bottom flanges, one projection being at the top of the block on one side and the

other at the base of the block on the other side, as clearly shown in the drawings.

1 represents the central web of the block; 2 and 3 the top and base flanges, respectively, and 4 the ends, having offset inclined faces 5 30 and 6.

7 are the vertical ribs, 8 the inclined ribs, and 9 and 10 the projecting side portions of the block, top and bottom, respectively. The top and bottom flanges and the vertical and inclined ribs are beveled, their sides being inclined from the point where they spring from the central web to their outer face.

I claim as my invention—

The design for a filling-block for fireproof floors, substantially as described and as shown in the accompanying drawings.

In testimony whereof I have signed my name to this specification in the presence of two subscribing witnesses.

FREDERICK SELBY.
